(No Model.)

J. H. MILLER.
CLEVIS FOR IRON STRUCTURES.

No. 583,537.

Patented June 1, 1897.

UNITED STATES PATENT OFFICE.

JOHN H. MILLER, OF BATAVIA, ILLINOIS, ASSIGNOR TO THE UNITED STATES WIND ENGINE AND PUMP COMPANY, OF SAME PLACE.

CLEVIS FOR IRON STRUCTURES.

SPECIFICATION forming part of Letters Patent No. 583,537, dated June 1, 1897.

Application filed December 10, 1896. Serial No. 615,096. (No model.)

To all whom it may concern:

Be it known that I, JOHN H. MILLER, a citizen of the United States, residing at Batavia, in the county of Kane and State of Illinois, have invented a certain new and useful Improvement in Clevises for Iron Structures, which is fully set forth in the following specification, reference being had to the accompanying drawings, in which—

10 Figure 1 is a side elevation of a portion of a windmill-tower post with a brace-rod secured thereto by a clevis constructed according to my invention. Fig. 2 is a horizontal section on the line 2 2 of Fig. 1. Fig. 3 is a plan view of my said clevis with some parts broken away. Fig. 4 is a vertical section on the line 4 4 of Fig. 3. Fig. 5 is a front end view of my said clevis.

15 My invention relates to iron structures, and has for its object to provide a clevis adapted to attach the brace-rods to the posts of water-towers and other iron structures, particularly to posts of that form of construction known as the "Larimer column."

20 According to the construction generally employed hitherto the clevis has been bolted to the tower-post and the brace-rod secured to the clevis by a rivet-head. The brace-rod was tightened by a turnbuckle disposed at some 25 point midway thereof. As a result of this construction the rivet-heads of the brace-rods often snapped off under the contraction and the brittleness of the metal consequent upon cold weather; and, further, the method of attachment of the clevis to the tower-post was defective in that too much strain, in the nature of a shearing stress, was brought upon the attaching-bolts.

30 My invention is designed to remedy these 40 defects by a construction which will now be specifically described.

Referring to the drawings by letter, A represents a tower-post which is herein illustrated as being of the Larimer-column form, 45 as shown in horizontal section in Fig. 2, and comprising the two bent girders A' and A², joined together by the interposed I-beam A³ and rivets A⁴ in the ordinary manner. Each 50 of the girders A' and A² terminates in a double flange a, and it is to such flange that my clevis is adapted to be secured. My said

clevis is of two-part construction. Each of the parts B and B' comprises a side piece B² and at one end thereof an end piece B³, disposed at right angles thereto and formed with an inner curved bearing-surface B⁴. Each of the end pieces B³ is provided with a perforated ear B⁵, adapted to receive a rivet B⁶. To the foregoing extent the two parts of my clevis are identical in construction. Integral with the remaining end of the part B, I form a cross-head B⁷, provided with the reinforcing-flanges B¹³ and with the perforation b', adapted to receive the end of the brace-rod. The opposite end of the cross-head B⁷ is formed with a neck B⁸ and head B⁹, the said head being provided with the lips or lugs b² b³. In the remaining end of the part B' is formed an aperture b⁴, adapted to admit the head B⁹ and provided, preferably, with a beveled edge b⁵, against which the lug b³ is adapted to bear when the neck and head are drawn forward in the aperture.

To explain the operation of my clevis, the construction of which is hereinabove described, the two parts are secured on opposite sides of the web by one of the column-girders, as shown particularly in Fig. 2, by the rivet B⁶ passing through the ears B⁵ and the said web. The head B⁹ passes at the same time through the aperture b⁴ and engages therewith in the manner already described. The end of the brace-rod C, threaded as at C', is inserted through the perforation b' of the clevis cross-head and is secured and tightened therein by the nut C². The clevis thus not only attaches the brace-rod to the tower in a manner which obviates the use of a rivet-head for said brace-rod, but also serves as a turnbuckle for adjusting and tightening the said brace-rod. The curved bearing-surfaces B⁴ are adapted to contact with and bear against the inner surfaces of the flange a, and thus to relieve the rivet B⁶ of all shearing stress, leaving it only the function of holding the two ends of the clevis together. The same curved bearing-surfaces enable the clevis to be given a singular degree of angular adjustment without interfering with its bearing against the said flange. Finally, the lock, by which the two outer ends of the two clevis parts are held together, is held more

firmly as the tension upon the clevis is increased.

It will be seen that several changes may be made in the construction described without departing from the spirit of my invention. I do not limit myself to the specific form shown, therefore; but

What I claim, and desire to secure by Letters Patent, is—

- 10 1. In a clevis adapted to secure a brace-rod to a tower-post, the two side pieces B²; the end pieces B³ adapted to bear against flanges upon the said post; means for attaching the said end pieces to the post; the cross-head B⁷ integral with one of the side pieces B² and adapted to lock with the other side piece; and means for securing the brace-rod to the said cross-head.
- 15 2. In a clevis adapted to secure a brace-rod to a tower-post, the two side pieces B²; the end pieces B³ provided with curved bearing-surfaces B⁴ adapted to bear against flanges upon the said post; means for attaching the

said end pieces to the post; the cross-head B⁷ integral with one of the side pieces B² and provided with a head B⁹ adapted to lock in an aperture b⁴ in the remaining side piece, and further provided with an aperture b' adapted to receive the end of the brace-rod; and means for securing the said brace-rod in the said aperture.

3. In a tower, the tower-post A carrying flanges a; a clevis comprising the side pieces B², the end pieces B³ adapted to bear against the flange a, means for securing the end pieces to the said post; the cross-head B⁷ provided with an aperture b' integral with one of the side pieces B² and provided with means adapted to lock the same with the remaining side piece; and the brace-rod C provided with the threaded end C' passing through the aperture b', and the nut C².

JOHN H. MILLER.
